UNITED STATES PATENT OFFICE

154,409

DESIGN FOR A GAME BOARD STAND

Walter F. McNamara, Chicago, Ill.

Application January 24, 1947, Serial No. 136,364

Term of patent 14 years

(Cl. D34—5)

To all whom it may concern:

Be it known that I, Walter F. McNamara, a citizen of the United States, residing in Chicago, in the county of Cook and State of Illinois, have invented a new, original, and ornamental Design for a Game Board Stand, of which the following is a specification, reference being had to the accompanying drawing, forming part thereof.

In the drawing:

Fig. 1 is a perspective view of a game board stand embodying the design of the present invention;

Fig. 2 is a front elevational view thereof;

Fig. 3 is a rear elevational view thereof on a reduced scale; and

Fig. 4 is a side elevational view thereof on a reduced scale.

I claim:
The ornamental design for a game board stand, substantially as shown and described.

WALTER F. McNAMARA.
